UNITED STATES PATENT OFFICE.

MAURICE S. WETZEL, OF SPRING LAKE, MICHIGAN.

BOMB.

Application filed March 17, 1919. Serial No. 283,073.

To all whom it may concern:

Be it known that I, MAURICE S. WETZEL, a citizen of the United States, residing at Spring Lake, in the county of Ottawa and 5 State of Michigan, have invented new and useful Improvements in Bombs, of which the following is a specification.

The present invention relates to bombs, such as are used for spectacular and for 10 advertising purposes, and one of its objects is to provide a bomb of that character improved in various features of construction; a further object is to provide such a bomb, one part of whose walls is adapted to burst 15 more readily than another; a further object is to provide in such a bomb means for preventing advertising matter and the like therein contained from injury arising from the bursting of the bomb.

20 These and any other objects hereinafter appearing are attained by, and the invention finds preferable embodiment in, the structures hereinafter particularly described and illustrated by the accompanying drawings, in which:

Figure 1 is a central longitudinal section of a bomb of the character described, certain parts being broken out;

Figure 2 is a transverse section of the 30 same taken on a plane corresponding to line 2-2 of Figure 1, the envelope and binding cords being removed;

Figure 3 is a top plan view of the same, the envelope being removed;

35 Figure 4 is a top view of the side wall, the flaps of the same not being bent over; and Figure 5 is a fragmentary view of a modified form of the bomb's bottom wall, etc.

In the embodiment of the invention chosen 40 for illustration by the drawings and for detailed description in the body of this specification, the cylindrical bomb shown in Figures 1, 2, 3 and 4 has the top end wall designated generally 1, the bottom end wall designated generally 2 and the side wall 3. This

45 side wall is composed of two plies of suitable material, as paper board. At the upper end of the side wall, both plies are slit to form flaps, the flaps 4 of the outer ply 5 being in "staggered" relation to the flaps

6 of the inner ply 7, as particularly shown in Figure 4. The flaps 4 are folded over and securely fastened as by gluing to the member 9 of the top wall, and the flaps 6

55 are folded over the lower member 8 of the top end wall and are securely fastened as by

gluing to and between the lower member 8 and an upper member 9 of the top end wall, thus "breaking joints" between the flaps of the two plies as particularly shown in Figure 2. In order that the joint between the side wall and the bottom end wall may be more frangible than that between the side wall and the top end wall (for the reason hereinafter given), the inner ply is not provided with flaps at its bottom, the flaps 10 of the outer ply however being bent over and may be fastened as by gluing to the member 11 of the bottom end wall. Outer members 12 of the top end wall and 13 of the bottom end wall are provided with peripheral notches 14 uniformly spaced apart. The walls are securely bound together by a cord 15 seated in these notches and tightly wound around the bomb across and parallelly 75 between the ends and outside the side wall. A suitable envelope 16 tightly surrounds the walls and cords, being glued in place, and forms a chamber 17 beneath the bottom wall wherein is contained the firing charge 18 of 80 the bomb, which is ignited by lighting the end 19 of the fuse 20 when the bomb is inserted into the firing mortar.

In a chamber 21 in the bomb suitable advertising matter or a float may be contained, to be released by the bursting of the bomb in the air. Beneath a partition 22 the bursting charge 23 is contained in the chamber 24, which charge is ignited by the slow fuse 25, which is ignited by the firing 90 charge. Suitable packing 26 (as sawdust) may be placed on the top of the partition 22 and beneath the float in the chamber 21 to protect the float from injury by the explosion of the bursting charge. To further 95 insure the float against such injury, stop struts 27 extend in the chamber 21 between the inside of the top wall and the adjacent (upper) side of the partition, which hold the partition from being blown upwardly by 100 the bursting of the bomb. Similar struts 28 in the chamber 24 extend between the bottom wall and the adjacent (under) side of the partition as shown. All these struts 105 may be secured in position by gluing to the inside of the side wall.

It will be seen that when the bomb bursts, it bursts at the bottom, opening out somewhat like an umbrella to release the float carried in chamber 21. The float is thus 110 not injured by such bursting. This bursting at the bottom is effected by the charge

being placed in that end of the bomb which is remote from the float, the joint between the side wall of the bomb and the end wall adjacent the bursting charge being at least 5 as frangible as the joint between the side wall and the top wall which is remote from the bursting charge. This end is more certainly effected by the first mentioned joint being distinctly more frangible than the 10 second mentioned joint.

In Figure 5, a modified construction of the bottom end wall 2 is shown wherein this wall is provided with a circular opening 45, large enough to readily supply there- 15 through the bursting charge to the chamber 24. This opening is stopped with a plug 46 having an orifice 47 therethrough adapted to contain the fuse 25. It will be seen that the bomb may be stored and shipped without the bursting charge therein, and when it is desired to supply such charge the plug may be removed and the chamber 24 filled with the charge, after which the plug with the fuse 25 inserted into its orifice 47 may 20 be driven in tightly and secured in place as by gluing.

The cord 15 crosses the lower end wall in the same manner as it crosses the upper end wall shown in Figure 3; so that no portion 30 of the cord intersects the center of the end wall. Thus a space remains in the center of the wall for the opening 45 in no wise interfering with the cord's position.

It will be seen that the inner end of the 35 fuse 25 has a lateral extension 48, whereby the ignition of the bursting charge is made more certain.

The invention being intended to be pointed out in the claims, is not to be limited to 40 or by details of construction shown or described.

I claim:

1. In a bomb of the character described; an end wall; a two-ply side wall having at 45 its end flaps folded over and fastened to

the end wall, the flaps of one ply being in staggered relation to those of the other ply.

2. In a bomb of the character described; an end wall comprising two members; a two-ply side wall having flaps at its end, the flaps of one ply being folded over and fastened between said members and the flaps of the other ply being folded over and fastened to the opposite side of one of said members, the flaps of one ply being in staggered relation to those of the other ply.

3. In a bomb of the character described; end walls; a side wall having flaps at each end, and comprising two plies between the flaps at one end and the flaps at the other end, there being two plies of flaps at one end only, the flaps being folded over and fastened to the end walls respectively, the flaps of one ply of the two-ply end of the side wall being in staggered relation to those of the other ply of said two-ply end of the side wall.

4. In a bomb of the character described; end walls having peripheral notches; a side wall; a cord seated in the notches and wound around the bomb between and across its ends and outside the side wall.

5. In a bomb of the character described; end walls having peripheral notches; a side wall; a cord seated in the notches and wound around the bomb between and across its ends and outside the side wall; and an envelope enclosing the walls and the cord and containing a firing charge.

6. In a bomb of the character described; end walls having peripheral notches; a side wall; a cord seated in the notches and wound around the bomb outside the side wall and between the end walls and crossing the end walls at a distance from the center thereof.

In testimony whereof I have hereunto set my hand at Grand Rapids, Michigan, this 13th day of March, 1919.

MAURICE S. WETZEL.
